UNITED STATES PATENT OFFICE

102,483

DESIGN FOR COMBINED TRUCK FLARES AND SUPPORTING BRACKET THEREFOR

James H. Horsley, Chicago, Ill.

Application July 27, 1936, Serial No. 64,090

Term of patent 14 years

To all whom it may concern:

Be it known that I, James H. Horsley, a citizen of the United States and resident of Chicago, in the county of Cook and State of Illinois, have invented a new, original, and ornamental Design for Combined Truck Flares and Supporting Bracket Therefor, of which the following is a specification, reference being had to the accompanying drawing, forming a part thereof.

Figure 1 is a front elevational view of a set of nested truck flares showing my new design;

Figure 2 is a side elevational view of the same;

Figure 3 is a rear elevational view of the same;

Figure 4 is a top plan view of the same; and
Figure 5 is a bottom plan view of the same.

The article forming the basis of this application is a bracket, within which a plurality of truck flares, of the type employed on highways as warning signals to approaching drivers, are nested for carrying the same on an automobile, truck or other vehicle for use when the occasion may arise.

I claim:

The ornamental design for combined truck flares and supporting bracket therefor, substantially as shown and described.

JAMES H. HORSLEY.
